DIGGING AND DISINTEGRATING MACHINE FOR LUMP SOLIDS

Alfred Stauffer, Honey Brook, Pa., assignor to Lukens Steel Company, Coatesville, Pa., a corporation of Pennsylvania

Application April 11, 1951, Serial No. 220,378

2 Claims. (Cl. 97—10)

This invention relates to equipment for disintegrating lump solids and is particularly concerned with a mobile unit adapted to travel from place to place and especially adapted to directly dig up solids-containing earth, for instance the soil of cultivated lands, for the purpose of disintegrating stones or lump rock in such soil.

Equipment of this general kind is shown in my prior application, Serial No. 110,699, filed August 17, 1949, and issued April 20, 1954 as Patent No. 2,675,969, upon which the present invention is an improvement.

It is an object of the present invention to provide a machine of this kind as a mobile unit carrying both the stone disintegrating apparatus and also the earth-digging and conveyor or feed mechanism by which the stones are delivered to the disintegrator.

In such an integrated mobile unit, special problems arise with respect to weight distribution and the handling of the forces and loads incident to digging of the earth, and the arrangement of the present invention takes these factors into account in a novel manner to be explained more fully hereinafter.

In general, mobile unit of the invention comprises a frame structure with pairs of supporting wheels at the forward and rear ends thereof. The disintegrating equipment is disposed adjacent to the rear wheels and the digging and feeding conveyor is located with its discharge end adjacent to the disintegrator and with its digging end adjacent to the opposite end of the unit. Since the digging action exerts a substantial load in the downward direction at the forward end of the unit, the invention contemplates locating the engine for driving the disintegrator at the rear end of the unit, i. e., adjacent to the disintegrator itself, so that the major portion of the weight of both the disintegrator and the engine is carried by the wheels at the rear end and is thus not imposed on the front wheels, the latter thereby being relieved of most of the loads except for a portion of the weight of conveyor parts and the load incident to digging.

The power drives of the disintegrator, on the one hand, and of the digging conveyor, on the other hand, are arranged through separate transmissions. In fact, in the preferred arrangement the engine at the rear serves only to drive the disintegrator and the conveyor power is derived advantageously by the extension of a flexible power shaft forwardly of the unit, which shaft is adapted to be coupled with a power source external of the unit, for instance on a tractor by means of which the unit is transported.

In accordance with another aspect of the invention mechanism is provided for raising and lowering the digging or receiving end of the conveyor with reference to the frame of the unit, this mechanism comprising a two-position power device, having one position corresponding to the digging position of the receiving end of the conveyor, and the other position corresponding to the traveling position of the unit in which the receiving end of the conveyor is raised above the ground level.

In association with this two-position conveyor ad-

2

justing mechanism, provision is made for vertical adjustment of the front wheels of the unit with reference to the frame in relatively fine increments, whereby to enable fine regulation of the digging depth.

5 The invention still further contemplates special arrangements in the mounting of the conveyor, including a spring suspension serving to relieve the vertical adjusting mechanism of a portion of the load or weight of the digging end of the conveyor. Other features of importance 10 in the mounting of the conveyor include a horizontal pivot located near the rear or discharge end of the conveyor, but preferably spaced somewhat from the extreme discharge end, at which the power drive for operating the conveyor is connected to the moving conveyor elements. Considerable simplification of structure and other advantages relating, for example, to service and maintenance problems, is thereby afforded, as will further appear.

20 Still another feature of importance in connection with the mounting of the conveyor on the unit is the provision of vertical guides which are disposed intermediate the horizontal conveyor pivot and the digging end thereof, in order to prevent undesired lateral distortion of the conveyor which might otherwise occur when one side edge 25 or the other of the digging end encounters an obstacle during digging.

In addition to the foregoing the invention also contemplates the provision of means for breaking up or disintegrating earth lumps dug up by the conveyor prior to the delivery thereof to the disintegrator. As will further appear, this mechanism is advantageously arranged intermediate the ends of the conveyor, in such manner as to disintegrate earth lumps and effect separation of the earth from the stones or other solids prior to discharge thereof 35 to the disintegrator itself.

In considering another aspect of the invention, it is first pointed out that the conveyor is made up of spaced conveyor elements through which materials of small size may readily drop and return to the ground. However, with 40 such construction, from time to time stones may become caught between the spaced elements of the conveyor in a manner preventing them from being discharged into the disintegrator. Such stones would again be carried back to the receiving end of the conveyor and might cause 45 damage to parts of the machine. With this in mind the invention contemplates provision of means for dislodging such stones from between conveyor elements in the region of discharge to the disintegrator.

How the foregoing and other objects and advantages 50 are attained will appear more fully from the following description of the accompanying drawings, in which—

Figure 1 is a side elevational view of mobile machine constructed in accordance with the present invention;

Figure 2 is a plan view to an enlarged scale of a portion 55 of the machine, particularly illustrating the conveyor;

Figure 3 is a rear elevational view of the machine on the same scale as Figure 1;

Figure 4 is a horizontal sectional view taken substantially as indicated by the line 4—4 on Figure 1 but to 60 an enlarged scale;

Figure 5 is a view on the scale of Figure 4 but illustrating certain details; and

Figure 6 is a vertical sectional view of one of the front wheel supports taken as indicated by the line 6—6 on 65 Figure 1.

In considering the structure and operation of the equipment of this invention, it is first to be noted that the machine is usable in a variety of different ways and for a variety of different purposes. For example, a wide variety of solid materials may be fed to the machine for purposes of disintegration, such as crushed rock, ores, and mixtures of materials of different consistency, in-

cluding, for example, earth-like materials containing more or less solid lumps.

Many features of the machine are especially adapted to a mobile unit adapted to be transported over cultivated lands for the purpose of picking up the soil, separating the rocks from the soil, returning the soil to the ground, and disintegrating the rocks and thereafter returning the rock powder or particles to the ground. Since most features of the equipment are especially adaptable to this latter purpose the invention is described hereinafter in that association.

The mobile disintegrator unit of my invention comprises in general, frame structure A, rear supporting wheels B, front caster wheels C, disintegrator equipment D disposed adjacent the rear wheel B for disintegrating solid materials such as rocks which are fed to the disintegrator, an engine E for driving the disintegrator D located adjacent thereto, earth digging and conveyor mechanism F for delivering the solid materials to the disintegrator, flexible drive shafting G for driving the conveyor mechanism having flexible connection with and receiving drive from an engine on a tractor to which the mobile unit is coupled, and power lift means H for moving the conveyor mechanism F from a digging position to a non-digging or raised traveling position above the ground level.

The frame structure A comprises longitudinally extending side frame members 7, 7 spaced laterally apart a distance to accommodate the conveyor and disintegrator mechanisms therebetween, a front cross member 8 having extended end portions 9 curved rearwardly and terminating in sockets 10 in which the shanks 11 of the caster wheels C are swiveled. The frame also includes a rear cross member 12, and an intermediate cross member 13.

The disintegrator equipment D comprises a disintegrating impeller 14 having its shaft 15 extending in a direction lengthwise of the machine and rotatably mounted in bearing 16, 16 carried by the cross members 12 and 13 of the frame, a feeding impeller 17 mounted adjacent the disintegrating impeller 14 for rotation about an axis inclined from the vertical to direct solid materials to the disintegrating impeller, housing 18 for the disintegrating impeller supported on the frame, and housing 19 for the feeding impeller supported from the frame by means of bracket structure 20.

The rear supporting wheels B are mounted on an axle 21 located at the rear end portion of the frame structure A and supported therefrom by means of axle supports 22, it being noted that the disintegrating and feeding impeller mechanisms are located adjacent the rear axle so that the weight thereof is carried at the rear portion of the mobile unit by the rear wheels.

The engine E for driving the disintegrating impeller and the associated feeding impeller is mounted generally vertically thereabove on a platform 23 suitably supported from the frame as by means of hood structure 24. Thus, the weight of the engine as well as the weight of the associated disintegrating equipment is carried in large part by the rear wheels B.

The disintegrating impeller 14 is driven from the engine E by means of belt drive 25 and the feeding impeller 17 is driven from the impeller 14 by means of belt drive 26. The feeding impeller 17 is driven at a lower speed than the disintegrating impeller 14 as by means of suitable reduction gearing (not shown) connected from the driven shaft 27 of the belt drive 26 to the feeding impeller shaft 28 and located in a gear housing 29. The use of friction belt drives at some point in the drive transmission for the impellers is of advantage because of the cushioning action thereby introduced into the drive system. In consequence, particularly severe loads or blows experienced by the impellers are not as likely to damage the drive transmissions, as would be the case where gearing and shafting comprise the entire transmission system.

The earth digging and conveyor mechanism F com-

prises a conveyor chain 30, laterally spaced drive sprockets 31 at one end of the conveyor chain mounted on a drive shaft 32 extending crosswise of the unit and journaled at one end in a bearing 33 supported on the main frame member 7, the shaft being supported at its other end in a bearing 34 of the gear housing 35 supported from the main frame by a bracket 36. The conveyor has upright plate members 37 constituting side walls for the conveyor, chain guide rollers 38 at the other end of the conveyor rotatably mounted on stub shafts 39 carried by the side members 37 and a plurality of other spaced chain guide rollers 40 and 41 carried by the side members. The rollers 38 and 40 are of conical shape to provide for sidewise centering of the chain. The links of the conveyor chain are in the form of crossbars 42 spaced apart a distance such that lump solids of the size to be disintegrated will be conveyed by the chain while permitting dirt and smaller particles to fall or sift through to the ground.

The conveyor mechanism F is located with its discharge end toward the rear of the unit adjacent the disintegrator D, and with its digging or receiving end at the front of the unit adjacent the front wheels E; and the conveyor is mounted with freedom for vertical swinging movement of the digging end by means of a horizontal pivot or shaft 43 offset forwardly from the conveyor drive shaft 32. This shaft 43 is mounted in supports 44, 44 carried by the main side frame members 7, 7 of the unit.

It is pointed out that by having the pivot 43 in a mounting independent of the mounting of the conveyor drive shaft 32, assembly of the unit is simplified and service and maintenance costs are reduced. For example, in the event of failure such as would necessitate removal of the drive shaft 32 or of the sprockets 31 these parts can be removed and replaced without disturbing the mounting of the pivoted structure, which would not be the case if this structure were pivoted on the chain drive shaft, because removal of the shaft would leave the pivoted structure without support. It is also to be observed that with my arrangement when the drive shaft is removed the conveyor chain is still supported by the pivoted structure and this simplifies re-assembly of the chain on the sprockets.

The flexible drive shafting G for driving the conveyor comprises a universal shaft 45 having driving connection with the engine of a tractor by which the unit is propelled, a belt drive 46 connecting the shaft 45 with a rearwardly extending shaft 47 located at the side of the conveyor and supported from the main frame of the unit, and gearing 48 connecting the shaft 47 with the conveyor drive shaft 32.

The power lift means H for controlling the vertical swinging movement of the conveyor mechanism comprises a two-position gear device 49, a crank 50 rotated by the gear device 49 (see Figure 4), a manually operable trip bar 51 for controlling the gear device, a drive motor 52, and a switch 53 associated with the trip bar for controlling the motor 52. The gear device 49 includes a driven gear 54 secured on a shaft 55, bearings 56, 56 for the shaft provided in a housing 57 secured to a mounting bracket 58 carried by the cross member 8 of the main frame. A driving gear 59 on the shaft of the motor 52 meshes with the driven gear 54, and a positioning disc 60 having a pair of opposed stop notches 61, 61 is engageable by a stop rod 62 to effect step rotation of the gear 54.

The crank 50 is adjustably secured to the disc 60 by means of screws 63 and arcuate slots 64 so that the position of the crank with respect to the position of the notches 61 may be adjusted. The stop rod 62 is secured to the trip bar 51 by means of bracket 65 and nuts 66. The switch 53 is mounted on the bracket 58 and is operated to close a circuit to the motor 52 when the trip bar is tripped, i. e., when it is moved to the left as viewed in Figure 4. The trip bar is provided with

teeth at 67 which engage the teeth of the gear 54 when the bar is in its normal position as shown in Figure 4.

The power lift means H is connected to the conveyor mechanism F by means of linkage comprising a bellcrank 68, one arm 69 of which is connected to the crank 50 by a link 70 and the other arms 71, 71 of which are connected to the ends 72, 72 of semi-elliptic springs 73—73. The ends 72, 72 of the springs 73 are shackled to the side members 37, 37 of the conveyor at 74, 74 and the other ends 75, 75 of the springs are shackled to the main frame members 7, 7 at 76, 76. These springs in addition to providing vertical cushioning at the front portion of the machine also provide partial unloading of the power lift means H which is particularly useful during raising movement of the conveyor.

Assuming now that the conveyor F is in the full-line position of Figure 1, i. e., in its raised traveling position clear of the ground, and that it is desired to lower it into its digging and feeding position indicated in dot-and-dash lines at 77 in Figure 1 (in which position the plow members 78 provided at the lower front portion of the conveyor will dig into the ground), the operator pulls on the cable 79 attached to the trip bar 51 to disengage its teeth 67 from the gear 54 and to simultaneously withdraw the stop rod 62 out of the stop notch 61 and close the switch 53. The motor then causes rotation of the gear 54, and the trip bar, after being released, causes the stop rod 62 to ride on the peripheral face of the notched disc 69 until it has made one-half revolution holding the teeth of the trip bar out of engagement with the gear 54. At the end of this one-half revolution the rod 62 drops into the disc notch and the bar teeth 67 engage the gear 54 to hold the device in this position. As the above takes place the crank is rotated one-half revolution to assume a position 180° from the position shown in Figure 1, and the bellcrank is rocked to move the conveyor down into the lowered position shown in dot-and-dash lines in Figure 1. In order to raise the conveyor into its upper position again, the above operation is repeated, it being noted that the semi-elliptical springs 73 act to relieve the lift device of a portion of the load or weight of the digging end of the conveyor in this upward lift.

As the unit travels along with the conveyor in its downwardly inclined or digging position the plow member 78 dig up the ground, and the earth with its solids is picked up by the conveyor and as it is fed up the incline loose earth and the smaller particles sift through the conveyor and the large solids are fed along and are delivered at the discharge end of the conveyor to the inclined feed impeller. The feeder impeller throws the lump solids into the disintegrating impeller in the manner more fully shown in my copending application above identified. After disintegration the particles are discharged back to the ground through a discharge opening 89.

In the event that earth lumps such as clods of sod or wet soil are dug up and carried along by the conveyor I provide mechanism for breaking up such lumps prior to the delivery thereof to the disintegrator. This mechanism takes the form of upwardly displaceable breaker elements 81 located intermediate the receiving and discharge ends of the conveyor. The breaker elements 81 are constructed of heavy plates 82 having their rear ends curved upwardly and pivoted at their front ends for free swinging movement on a pivot rod 83 extending crosswise of the conveyor and secured in the side guide plates 37. As will be seen from Figure 2 I have provided two such elements pivoted on the rod 83 for independent swinging. In operation these breaker elements jog up and down rather violently and thus break up the clods or lumps underneath them. As a further aid in breaking up these lumps the top of the elements are constructed in the form of boxes 84 which may be filled with rocks to add weight to the elements.

In order to prevent damage to the conveyor chain when

the mobile unit is being transported from place to place with the conveyor idle in raised traveling position, I prefer to support the breaker elements 81 in a position above the chain as indicated in dot-and-dash lines in Figure 1. This is accomplished by first removing the cross brace rod 85, then swinging the breaker elements upwardly and then replacing the brace rod and allowing the breaker elements to rest thereon.

As has been pointed out above the conveyor is made up of bars spaced apart a distance such that solids of large size will be conveyed, while permitting materials of smaller size to fall through to the ground. I have found that with such construction stones are caught between the bars from time to time and without provision to the contrary the caught stones instead of being discharged to the disintegrator equipment are carried around by the conveyor toward the receiving end thereof, with the possibility of incurring damage to the machine. For example a caught rock carried around at the discharge end of the conveyor could damage the adjacent portion of the housing 19 of the impeller 17, and one carried around at the receiving end could damage the plow structure or cause breakage of the chain. Also should a large number of rocks be caught in the conveyor clogging would result.

I have overcome such difficulties by providing a plate beneath the conveyor bars at the discharge end of the conveyor for dislodging caught stones from the conveyor. Preferably this plate is curved to the form of a cylinder 86 extending between the spaced drive sprockets 31 of the conveyor and of a diameter approaching the root diameter of the sprocket teeth. Thus as the caught rocks engage the surface of the cylinder they are forced out from between the bars and discharged to the disintegrator.

Reverting now to the mounting of the engine E and the disintegrator equipment D adjacent the rear wheels B, it is pointed out that since the digging action of the conveyor exerts a substantial load in a downward direction at the forward end of the unit such rear mounting of the engine and disintegrator equipment is of importance because the major portion of their weight is thus carried by the rear wheels and therefore is not imposed on the front wheels. Consequently the front wheels are relieved of most of the loads except for a portion of the weight of conveyor parts and the load incident to digging.

In order to position the conveyor laterally with respect to the main frame I provide, in addition to the normal lateral positioning effect of the springs 73, lateral positioning members 87 at a point intermediate the conveyor pivot and the digging end thereof. These members are preferably associated with the spring saddle supports and extend laterally inwardly therefrom to engage the side plates 37 for the conveyor and thereby laterally position it. Through this arrangement I prevent undesired lateral distortion of the conveyor which might otherwise occur when one side edge or the other of the plows 78 encounter obstacles during digging.

If it is desired to alter the depth of dig of the conveyor this can be accomplished by vertical adjustment of the caster wheels C as by means of adjusting screws 88 carried by the sockets 10 and nut 89 secured in the shanks 11 of the caster wheels, as will be clear from inspection of Figure 6.

I claim:

1. In a mobile unit for disintegrating hard lump solids, a disintegrating device mounted on the unit adjacent an end thereof, a digging conveyor having its digging end positioned adjacent the other end of the unit and having its discharge end positioned to deliver lump solids to the disintegrating device, a horizontal pivot for mounting the conveyor on the unit with freedom for vertical swinging movement of the digging end of the conveyor, a leaf

spring shackled at one end to the digging conveyor adjacent the digging end thereof and shackled at the saddle and other end to the unit, said spring extending from the region of the digging end of the conveyor toward the discharge end thereof, a bellcrank mounted on the unit, a link interconnecting one arm of said bellcrank and said one end of the spring, power operated mechanism mounted on the unit for vertically moving the digging end of the conveyor, and a link interconnecting the other arm of said bellcrank and the power operated mechanism.

2. In a mobile unit for disintegrating hard lump solids, a disintegrating impeller mounted on said unit toward one end thereof, a digging conveyor comprising a frame structure associated with earth-digging and feed mechanism, said conveyor having its digging end positioned adjacent the other end of the unit and having its discharge end positioned to deliver lump solids to the disintegrating device, said feed mechanism having spaced conveyor elements mounted to travel in a closed circuit defining a belt-like path, horizontal pivot means for mounting the conveyor frame structure on the unit, drive means for the conveyor elements mounted on a shaft journaled in said unit beyond the end of the frame structure and adjacent the discharge end of the conveyor, said pivot being located intermediate said drive means and the digging end of the conveyor, said elements being movable in a flight from the digging end of the conveyor past the frame struc-

ture of the conveyor and over said drive means, whereby said conveyor is free for vertical swinging movement about said pivot while maintaining the elements in said flight in engagement with said driving means.
